UNITED STATES PATENT OFFICE.

WILLIAM P. MCCOY, OF YONKERS, NEW YORK.

TOBACCO-SMOKING PIPE.

Application filed February 5, 1920. Serial No. 356,367.

To all whom it may concern:

Be it known that I, WILLIAM P. McCoy, a citizen of the United States, residing at Yonkers, in the county of Westchester and State of New York, have invented a certain new and useful Improvement in Tobacco-Smoking Pipes, of which the following is a specification.

The principal objectionable features which militate against the full enjoyment of tobacco smoke in pipes of the usual types are, first, the introduction of saliva through the mouthpiece or bit into the smoke channels, resulting in obstructing such channels, and 10 draining into the bowl of the pipe, thereby fouling the tobacco therein; second, the withdrawal of a portion of such saliva, often charged with other disagreeable materials, into the mouth of the smoker; third, the collection or deposit of moisture in the smoke channels of the pipe stem and bowl, caused by the condensation of the smoke vapor after it has passed through the smoldering tobacco in the bowl. This collection or accumulation 15 of moisture results in clogging the smoke channels and interfering with a free flow of smoke and also causes the bubbling or gurgling so disagreeable to all smokers. This condensed vapor, often mixed with 20 other obnoxious secretions finds its way into the bowl and fouls the tobacco therein, or may be drawn into the mouth of the smoker; fourth, the collection of moisture in the smoke channels of the pipe caused by the condensation of the breath of the smoker 25 when he casually injects his breath through the orifice in the mouth-piece or bit, which produces the same disagreeable results as stated above; and fifth, a so-called "hot smoke" caused primarily by drawing the smoke vapor into the mouth before it has had sufficient opportunity to "cool out" or 30 lower its temperature to the desired degree.

The object of the invention is to provide a pipe in which the foregoing objectionable features shall be eliminated, and which shall be practical in operation, easily and economically manufactured, readily assembled and disassembled, easily cleaned and freed 45 from disagreeable or unhygienic matter, and of light weight, comfortable balance, and pleasing appearance.

The invention consists in certain novel features and details of construction by which 50 the above objects are attained, to be hereinafter described and claimed.

The accompanying drawings form a part of this specification and show preferred forms of the invention.

Figure 1 is a vertical section through the 60 bowl and stem of a pipe of the "straight stem" type.

Figure 2 is a similar view showing the invention applied to a "curved stem" pipe.

Figure 3 is a vertical section through a 65 pipe bowl of modified form, adapted to serve with a straight or curved stem.

Similar letters of reference indicate like parts in all the figures.

Referring to Figure 1, A is the bowl of 70 the pipe which may be understood to be a briar root, meerschaum or other material, having a channel *a* leading downwardly from the bottom of the bowl cavity, and a socket at B to receive the stem.

The stem has a nipple C matching to and received in the socket B, in which is an inclined channel *c* forming a continuation of the channel *a* and leading to an enlargement or chamber D in the stem which for convenience of description will be termed the expansion-chamber. This expansion-chamber extends upwardly from the stem in domed form, as shown, and downwardly to 80 form a well or trap E closed below by any suitable plug, or preferably by a screw-cap F.

From the expansion-chamber D the stem curves upwardly as at G and thence downwardly as at H and terminates in the mouth-piece or bit J. Between the high point of the curve and the bit, and near the latter is a second enlargement of the stem formed in the lower portion thereof, providing a bit-chamber K in the smoke channel *h* having a well or trap L below closed by the screw-cap M.

The caps F and M are preferably in alignment with the base N of the bowl in this straight stem type, so that the pipe may stand alone in the upright position on a table or like surface. The smoke channel *j* in the bit is shown as curved upwardly to the bit orifice.

The hot smoke vapor from the bowl A passes through the channels *a* and *c* and is received in the expansion-chamber D where it is free to expand, circulate and cool, and give up much of its moisture by condensation on the walls of such chamber during 100 its relatively slow travel therethrough. As the walls and channels are downwardly in-

clined such moisture flows easily and freely to the trap E in which it collects.

From the expansion-chamber D the smoke vapor, relieved of much of its moisture, passes to the upwardly inclined channel g, of less cross-sectional area than the expansion-chamber, and is further cooled. Moisture deposited in this portion of the stem is led back by the walls of the channel g to the trap E, and similar deposition in the downwardly inclined channel h is received in the trap L of the bit-chamber K. The latter again slows the travel and gives the smoke vapor free opportunity to circulate, cool, and give up moisture which is received in the trap L. It then passes through the bit channel j to the mouth of the smoker, cooled and freed from any condensable deleterious or objectionable matter.

It will be noted that any saliva from the mouth of the smoker or moisture introduced by the breath will follow the walls of the bit channel and be led to the trap L.

In Figure 2 the bowl A¹, chamber D¹ and trap E¹ are similar to the corresponding parts in Figure 1, the channel g¹ extends angularly upward and has a bit-chamber K¹ and its trap L¹ located at a higher level as required by the curved stem.

In Figure 3 the expansion-chamber D² and trap E² are formed integrally with the bowl A² and is provided with a nipple R adapted to receive a stem of either of the types shown in Figures 1 and 2, as will be understood.

The functions performed by the corresponding parts are the same in all the forms

shown. In all of the forms the expansion chamber constitutes a place where the smoke enters rapidly from the bowl through the contracted passage therefrom and is permitted to expand and slow down and cool before passing through the stem.

By introducing absorbent cotton or like material into the chambers the smoke vapor may be filtered if desired without interfering with the action.

I claim:

1. A tobacco smoking pipe comprising a bowl having a channel extended downwardly from the bottom of the bowl cavity, and a stem, there being an expansion chamber communicating with said channel exteriorly and adjacent the bowl, the passage through the stem curved upwardly from said expansion chamber, and a bit chamber intermediate the mouthpiece and said expansion chamber.

2. A tobacco smoking pipe comprising a bowl having a channel extended downwardly from the bottom of the bowl cavity, and a stem, there being an expansion chamber communicating with said channel exteriorly and adjacent the bowl, the passage through the stem curved upwardly from said expansion chamber, a bit chamber intermediate the mouthpiece and said expansion chamber, a trap in the bottom of the expansion chamber, and a trap at the bottom of said bit chamber.

In testimony that I claim the invention above set forth I affix my signature.

WILLIAM P. McCOY.
